C. G. BORTHWICK

DEVICE FOR USE IN PRACTICING THE GAME OF GOLF

Filed Aug. 29, 1923

Inventor:

Craigie Gyle Borthwick
By William Clinton
— Attorney

UNITED STATES PATENT OFFICE.

CRAIGIE GYLE BORTHWICK, OF EDINBURGH, SCOTLAND.

DEVICE FOR USE IN PRACTICING THE GAME OF GOLF.

Application filed August 29, 1923. Serial No. 630,041.

To all whom it may concern:

Be it known that I, CRAIGIE GYLE BORTHWICK, a subject of the King of Great Britain and Ireland; residing at Kinnel Works, 5 Corstorphine, Edinburgh, county of Midlothian, Scotland, have invented new and useful Improvements in a Device for Use in Practicing the Game of Golf, of which the following is a specification.

- 10 My said invention has for its object to provide a simple and inexpensive device for use in practicing the game of golf, whereby if the head of the club, when "driving" or the like, does not swing, or pass, through 15 a predetermined path, it contacts with one or more flexible and vibratory projections, positioned round said path, and so as to indicate to the player the error, or errors, in the swing of the club.
- 20 In carrying out my invention according to one simple example, the device consists of a horizontal oblong frame provided with a mat of any soft or flexible material, and also a disc or half sphere, to represent a ball, 25 with a flexible connection, so that when struck it will turn over into a recess formed for it, or a captive ball may be used. On each side of the frame brackets are arranged with inwardly projecting and adjustable 30 parts, and also with downwardly projecting and adjustable parts, and one set of these parts may be arranged directly in advance of the position of the ball, and the other set some distance in the rear of the ball.

35 In order that my said invention and the manner of performing the same may be properly understood I hereunto append a sheet of explanatory drawings to be herein-after referred to in describing my invention.

40 Figures 1, and 2, are respectively a plan, and a side elevation of the improved device, Figure 3, is an end elevation. Figures 4, 45 and 6, are respectively a plan, side elevation and an end elevation of the bracket or holder for supporting the horizontal and depending adjustable parts, drawn to a larger size. In these drawings the same reference numerals are used to mark the same or like parts wherever they are repeated.

50 As shown in Figures 1, 2, and 3, of the drawings, the device consists of a horizontal oblong frame 1, provided with a mat 2, and also a flexible disc 3, to represent a ball, so that when struck it will turn over into a recess 4, formed for it in the mat 2. Instead 55 of the disc 3, a captive ball may be em-

ployed. The disc 3, has an aperture 3^a, (Figure 3), formed in it, said aperture representing, if an ordinary ball were used, the correct point of contact with the club head. 60 On each side of the frame 1, two brackets 5, 6, and 7, 8, are arranged, with inwardly projecting, vibratory, and adjustable parts 9, 10, and 11, 12, and also with downwardly projecting, vibratory and adjustable parts 13, and 14. One set of these parts being positioned in advance of the position of the disc 3, and the other set some distance in the rear of said disc.

65 The distance between the opposing ends of the parts 9, and 11, is preferably greater than that between the parts 10 and 12, and the lower end of the depending part 13, is higher than that of the depending part 14, so as to coincide with the curvature or arc 70 described by the head of the club. To avoid excessive swing of the parts 9, and 10, tapered blocks 9^a, and 10^a, are provided.

75 The arrow in Figure 1, indicates the direction in which the club head is traveling.

80 A preferred form of bracket, or holder, is shown in Figures 4, 5, and 6, in which the inwardly projecting parts 11, and 12, are held in a clip 15, by a pinching screw 16, and the supporting arms 17, and 18, of the 85 depending parts 13, and 14, are respectively held in an aperture of an upwardly extending member 19, by a pinching screw 20.

85 It is to be understood that I do not confine myself to any particular number of these inwardly projecting parts, as the characteristic feature of my invention consists in so positioning them relative to the ball, or disc 3, that a more or less perfect swing is essential to avoid contacting with any one 90 or more of the said projecting parts,—in other words, if a perfect swing is imparted to the club then the path of its head is unobstructed, on the other hand if the swing of the club is faulty, its head contacts with one or more of the projecting parts, and the position of the latter indicates the error, or errors, in the swing. For example, if the club head is too high it will contact with one 95 or other, or both, of the depending members 100 13, and 14, whereas if the club head is too low it will contact with the mat 2, in advance of the ball, and if too much to either side of a line drawn through the centre of the disc 3, it will contact with one or more 105 of the cross members 9, 10, 11, and 12.

110 The device is used as follows:—The frame

is placed on the floor, or ground, and the player takes up a position which in her, or his, opinion, will ensure a correct drive. The club is then swung in the usual manner, and if after striking the ball, and the swing more or less completed, without contacting with any of the projecting parts, on the frame, then it is assumed that a correct swing and drive has been made. The projecting parts 9, 10, 11, 12, 13 and 14, are made adjustable, for example, to allow of a certain latitude, which can be gradually reduced as the player becomes more proficient.

What I claim is:—

15 1. A device for use in practicing the game of golf, consisting of a frame provided with a disc or captive ball, means for supporting two cross members positioned in the rear of the ball and spaced apart and two cross members positioned in advance of the ball and spaced apart, and two depending members similarly positioned but at different levels, so that when a true swing is imparted to the club its head will describe an arc lying

25 between the cross and depending members without contacting with the frame or a part thereon substantially as set forth.

2. A device for use in practicing the game of golf, comprising a target, a plurality of inwardly projecting and depending flexible parts, the ends of said parts lying in an arc 30 covering said target.

3. A device for use in practicing the game of golf, comprising an oblong frame, a pair 35 of brackets at each side of said frame, a target disposed within the frame, elongated members adjustably supported in said brackets and extending into the frame, curved posts supported by the brackets at one side 40 of the frame and extending over said frame, and elongated members adjustably supported by and depending from the free ends of said posts, the ends of the elongated members and the depending members lying in an arc covering said target.

45 In testimony whereof I have signed my name to this specification.

CRAIGIE GYLE BORTHWICK.
